[57] **CLAIM**

The ornamental design for a “combined electronic computer, camera and docking station”, as shown and described.

DESCRIPTION

FIG. 1 is a front elevational view of a combined electronic computer, camera and docking station according to our design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a left side elevational view thereof with the cover of the computer in a closed position;

FIG. 8 is a right side elevational view thereof;

FIG. 9 is a rear elevational view thereof in a closed position;

FIG. 10 is a front elevational view thereof in a closed position;

FIG. 11 is a bottom view thereof in a closed position;

FIG. 12 is a top plan view thereof in a closed position;

FIG. 13 is a top, front and right side perspective view thereof in an open position;

FIG. 14 is a view similar to FIG. 13 with the camera rotated 90°; and,

FIG. 15 is a top, front and right side perspective view thereof in a closed position.
